UNITED STATES PATENT OFFICE.

EVERETT A. MARGESON AND CHARLES DAVID HERROLD, OF SAN JOSE, CALIFORNIA,
ASSIGNORS TO GERTRUDE ANNIE MARGESON, OF SAN JOSE, CALIFORNIA.

AUTOMATIC MULTIPLE-SWITCH-CONTROLLING MACHINE.

1,409,561.

Specification of Letters Patent.

Patented Mar. 14, 1922.

Original application filed March 29, 1920, Serial No. 369,780. Divided and this application filed August 4, 1920. Serial No. 401,153.

To all whom it may concern:

Be it known that we, EVERETT A. MARGESON and CHARLES DAVID HERROLD, citizens of the United States, residing at San Jose, in 5 the county of Santa Clara and State of California, have invented a new and useful Improvement in Automatic Multiple-Switch-Controlling Machines, of which the following is a specification.

10 This invention relates to an automatic multiple switch controlling machine and is a division of our copending application entitled "Automatic multiple switch controlling machine," filed March 29, 1920, Serial 15 No. 369,780.

One of the objects of the present invention is to provide an automatic multiple switch controlling machine whereby several independent electric circuits may be automatically controlled, and especially to provide a multiple switch controlling machine whereby one or more motor driven street indicating machines may be intermittently and independently operated.

25 Another object of the invention is to provide a multiple switch controlling machine, an indicating machine and an electric motor for driving the same and in conjunction therewith to provide means on the multiple 30 switch controlling machine for preparing a shunt circuit around the motor which is adapted to be closed by an automatic switch on the indicating machine and opened after a predetermined interval by another automatic switch on the multiple switch controlling machine.

Further objects will hereinafter appear.

The invention consists of the parts and the construction, combination and arrangement 40 of parts as hereinafter more fully described and claimed, having reference to the accompanying drawings, in which—

Fig. 1 is a side elevation of the automatic multiple switch controlling machine.

45 Fig. 2 is a front view of the same, partially broken away and partially in section.

Fig. 3 is a plan view of the indicating machine.

Fig. 4 is a side elevation of the same.

50 Fig. 5 is a partial side elevation of a

street car, showing the application of the invention.

Fig. 6 is an enlarged detail sectional view of the reversing switch drum.

Fig. 7 is a wiring diagram showing the 55 connections formed between the indicating machines and the automatic multiple switch controlling machine.

Fig. 8 is a section taken on the line shown 60 near the right end of Fig. 3.

Referring to the drawings in detail, and particularly to Figs. 1 and 2, which are the drawings of the automatic multiple switch controlling machine, A indicates a main frame of suitable construction, in which is 65 journaled a shaft 2. Turnably mounted on the shaft is a drum 3 and keyed to the shaft or otherwise secured thereto is a pair of rack gears 4, one on each side of the drum. The rack gears are right and left hand, or 70 in other words, reversed with relation to each other, and both gears are engaged by pawls 5, which are carried by the drum. Formed on the outerface of the drum is a 75 threaded or helix 6, and projecting from the face of the helix are pins or projections 7 which are adapted to intermittently rotate a pin gear 8 which is keyed but slidably mounted on a shaft 9. This shaft is supported in journal member 10 above the 80 drum, and secured on one end of the shaft is a wheel 11, on which is formed six cam projections such as indicated at 12. There are twelve pins on the pin gear 8 and a twelfth of a revolution is therefore transmitted to the pin gear and the shaft 9, together with the cam wheel 11 when the pin gear is engaged by a projection 7 carried by the helix. The shaft 2, together with the gears 4, and the drum 3, are mechanically 85 driven. The drive provided consists of a flexible shaft 13, which is positively driven from the car wheels by means of the gears 14. (See Fig. 5.) Turning movement imparted to the flexible shaft is transmitted through a jaw or a pin clutch such as shown at 15 to a shaft 16 and from this shaft to a vertically disposed shaft 17, which is journaled in the main frame A through a bevel gear train such as shown at 18. Se 100

95

cured on the shaft 17 is a worm 19, and intermeshing therewith and secured on one end of the shaft 2 is a worm gear 20. In other words a positive driving connection 5 is formed between the car wheels and the shaft 2, the speed of the shaft 2 being however materially lessened due to the gear reduction provided by the bevel gears 18 and the worm gears 19 and 20. The reduced 10 speed transmitted to the shaft 2 is again transmitted to the drum 3 through one or another of the rack gears 4 and the pawls 5; the driving connection formed depending upon the direction of rotation, that is one 15 pawl and rack will drive the drum in one direction and the opposite pawl and rack in the opposite direction. The pin gear 8 is flanged as shown at 8^a to embrace the thread or helix 7. It is therefore obvious that revolution 20 of the drum will impart a sliding movement to the pin gear. This movement is utilized to automatically break the driving connection between the rack gears 4 and the pawls 5. For instance, by referring to 25 Fig. 2, it will be seen that a crank arm 22 is pivotally secured to the main frame A as at 23. The upper end of this crank arm is engaged by the pin gear 8 when it has travelled a predetermined distance along 30 the shaft 9. A rocking movement will thus be transmitted to the crank arm 22, causing its upper end to swing upwardly and its lower end 24 inwardly. This will cause the lower end 24 to assume a position in 35 alignment with the adjacent or cooperating pawl 5, and as this is provided with a raised cam projection 25 (see Fig. 1), it is obvious that passage of the pawl under the arm 24 will cause depression of the cam end of 40 the pawl and raising of its opposite engaging end, thus freeing the pawl with relation to the cooperating rack gear and automatically breaking the driving connection. This automatic break between the drum and 45 one or the other of its driving connections is necessary. For instance, if a car is travelling on a certain run and steep hills or slippery weather is encountered, it is possible that the car wheels will slip while the 50 drum continues rotating. This is objectionable as it throws the drum or the pins carried on the helix out of time with the car, or in other words, causes streets to be announced or displayed before their proper 55 sequence as will hereinafter be described. Slippage of the car wheels will under all conditions cause the drum to advance and it will therefore cause it to display the street names too early. In fact slippage might 60 take place to such an extent as to display a street two or three blocks ahead of time of reaching the same. It is therefore obvious that the drum will turn its predetermined number of revolutions before the end of 65 the run is reached and that to correct the

slippage, it is only necessary to automatically disconnect the driving connection between the gears 4 and the drum. With the driving connection automatically broken by means of the crank arm 22, it is possible for shaft 70 2 to turn without transmitting further movement to the drum. The drum therefore remains stationary until the car reaches the end of its run and any slippage that may have taken place is thus corrected as the 75 car will now be reversed and will travel in the opposite direction.

Manually actuated means has also been provided for correcting the position of the drum. This is accomplished by first throwing out the pin clutch 15, for instance by means of a rocker arm 15^a and a connecting lever 15^b. A hand crank 26 is then grasped and rotated in the direction desired. This hand crank is secured on a shaft 27 journalled in the base of the main frame and this shaft in turn carries a sprocket gear 28, which transmits rotation to the shaft 17 through means of a chain 29 and a sprocket gear 30 secured on the lowermost end of 90 shaft 17. This permits the drum to be turned until the correct street is indicated and is only used when the car is side-tracked for some reason or another or possibly after having traversed another route. It may of course be rendered entirely inoperable under these conditions by disconnecting the clutch 15.

The construction of the drum, the mounting and driving of the same, and the means for adjusting or correcting its position has now been described, and it is therefore thought that the function of the cam wheel 11 should follow. This wheel, as previously stated, is provided with six cams 12 and is 100 intermittently rotated one-twelfth of a revolution. Pivotaly attached to the main frame, as at 31, at a point above the shaft 9, is a pair of switch arms indicated by numerals 32 and 33. The switch 32 makes 105 and breaks circuits hereinafter to be described between the double contacts 34 and 35, while the switch arm 33 makes and breaks circuits between the double contacts 36 and 37. The switches 32 and 33 will 110 hereinafter be known as the master switches and the circuits established or broken thereby will further be described. The switch arms 32 and 33 are moved from one position to another by means of the cams 12 and as 115 these only turn one-twelfth of a revolution when actuated, it is obvious that the switch arm 32 will either engage the contacts 35, for instance when resting in a recess of the cam 12, and that it will contact with the terminals 34 when engaged by a cam. The 120 operation of the switch arm 33 is similar, and as the switch arms are opposite to each other they will simultaneously move in one direction or another, thus engaging the dou- 130

ble contacts 35 and 37 in unison, or the double contacts 34 and 36 in unison. The whole function of the drum and the driving connections provided therefor is to intermittently change the position of the master switches 32 and 33. The machine is however provided with a reversing switch which cooperates with the switches 32 and 33, and also with other switches to be hereinafter described. This switch is generally indicated at B. It consists of a drum 38, which is supported by a shaft 39. This shaft is continuously rotated from shaft 17 by means of a worm gear drive 17^a, but rotary movement is only transmitted to the drum whenever the street car starts back at the end of its run. This is accomplished as follows: Secured interior of the drum on the shaft 39 is a pin 40, and interposed between the pin and the end of the drum is a coil spring 41, which holds the drum in frictional engagement with a collar 42 secured on the shaft. A friction drive or connection is thus formed between the drum and the shaft which becomes operable to turn the drum one-fourth of a revolution whenever the direction of rotation of shaft 17 is reversed. This will be more easily understood when it is stated that a segment-like lug 43 is secured on one end of the drum which is adapted to engage the upper portion of the frame at the points indicated at 44 and 45. For instance if the shaft 17 is turning in a direction which would cause the friction drive formed between shaft 39 and the collar 42 to turn in the direction of arrow a, (see Fig. 1) then drum 38 will rotate until the stop segment 43 engages the point or stop 44 formed by the frame. If the direction of shaft 17 is reversed, then it is obvious that the rotation of shaft 39 will be reversed and that the friction drive will thus cause the drum to revolve in a direction opposite to arrow a and it will revolve in this direction until the segment 43 engages the point of the main frame indicated at 45. An approximate one-fourth of a revolution is thus automatically transmitted to the reversing switch drum whenever the direction of rotation of shaft 17 is changed and as the direction of rotation of shaft 17 is only changed when the car is reversed, it can readily be seen that the reversing drum or switch only changes its position at each end of a given route or run, or at intermediate points.

The function of the reversing switch and its cooperation with the master switches 32 and 33 will hereinafter be described. It may, however, be stated that the drum is constructed of insulating material such as shown in Fig. 6 and that it carries in all twenty-two segments which are insulated therefrom. These segments are more clearly illustrated in Fig. 7 and will hereinafter be

referred to by reference numerals. The segments are engaged by sixteen separate spring actuated contacts, there being eight on each side of the main frame as indicated at C and D.

70

To fully understand the operation of the automatic multiple switch controlling machine, it is thought necessary to give a brief description of the indicating machines and the switches controlled thereby. The indicating machine is illustrated in Figs. 3 and 4 and is constructed as follows:

75

46 indicates a base plate on which is secured a pair of frame sections 47 and 48. Suitably journalled in said frame are a pair of rollers 49 and 50 and a pair of idlers 51 and 52. 53 indicates a belt constructed of any suitable material such as paper or fabric. This belt is carried by the rollers 49 and 50 and is guided by the idlers 51 and 52. One end of this belt is secured to the roller 49 and the opposite end to the roller 50. The rollers will therefore alternately serve as drivers and receivers and as the belt has street or station names printed or otherwise formed thereon, it is obvious that an intermittent movement must be transmitted to the rollers and the belt carried thereby to permit each name to be successively displayed through an opening 54, which is formed in a 90 casing 55 enclosing the entire mechanism.

95

The rollers 49 and 50 are in this instance driven by means of an electric motor 56 and this drive can be traced as follows:

100

57 indicates a horizontally positioned shaft which is journalled as at 58 in a bracket member 59 secured upon the base. Secured on one end of the shaft is a bevel gear 60 which intermeshes with a similar gear 61 upon the motor shaft, and secured to the opposite end of the shaft 57 is a worm gear 62 which intermeshes with a worm wheel 63. The gear 63 is secured on a shaft 64 and this is in turn journalled in the main frame as indicated at 65. Loosely mounted 105 on the shaft 64 is a pair of sprocket wheels 66 and 67 and connecting said sprockets with a pair of sprockets 68 and 69 are endless driving chains 71 and 70. The respective chains and sprockets are provided for the purpose of driving one or another of the belt supporting rolls 49 and 50 and this is accomplished as follows:

110

Suitably secured on the inner faces of the sprockets 66 and 67 are pins 66^a and 67^a. 120 Turnably mounted on the shaft 64, intermediate the sprockets 66 and 67, is a clutch member 72 and projecting from either end of said clutch and radially with relation thereto are pins 73 and 74. The clutch 72 consists of a sleeve in which is cut an angularly positioned slot 75. Secured to shaft 64 and projecting through said slot is a pin 75^a, and surrounding the sleeve and frictionally engaging the same is a pair of friction 125

130

clamp arms 76, the tension of which may be regulated by a screw 77.

The motor 56 is of the series wound type and is reversible and is therefore capable of transmitting power to shaft 57 in either direction. A drive transmitted through gears 60, 61, 62 and 63, in one direction will first cause the pin 75^a to travel from one end of slot 75, formed in the clutch sleeve, to the other. This causes the sleeve to move lengthwise of the shaft 64, pulling pin 74 into engagement with pin 66^a on sprocket 66. The longitudinal movement of the sleeve takes place while pin 75^a travels from one end of the slot to the other, sleeve 72 being prevented from rotating at this moment for the simple reason that it is held against rotary movement by the spring actuated clamp arms. The frictional engagement of said arms is however not sufficient to hold the sleeve against rotation when pin 75^a reaches the opposite end of the slot.

Power will therefore be transmitted through shaft 64, pins 75^a, sleeve 72, and pins 73 and 66^a, to sprocket 66, which in turn transmits power through chain 70 to the sprocket 68 and the roller 49. The belt 53 will thus unwind with relation to roller 50 and will pass over the idlers 51 and 52 to the roller 49 upon which it is wound, the sprocket 67 being loosely mounted on the shaft 64 will in this instance act as an idler and will otherwise be inactive as far as transmitting power is concerned, this being of course true only when power is being transmitted to the roller 49. If the direction of rotation of the motor is reversed it should be obvious that pin 75 will immediately travel to the opposite end of the slot and thereby force the sleeve 72 longitudinally into engagement with the sprocket 66. Power will then be transmitted through shaft 64, pins 74 and 67^a, to the sprocket 66 and through chain 71 power will be transmitted to sprocket 69 and the roller 50 driven thereby. The direction of travel of the belt 53 will thus be reversed and will wind itself about the roller 50 and will simultaneously unwind with relation to the roller 49.

The reversible motor together with the automatic clutch indicated at 72 makes it possible to drive the belt in either direction. This is of great importance when the indicator is employed in street car service as it is necessary to drive the belt in one direction when the car is travelling in one direction and it will consequently be necessary to reverse the travel of the belt when the car is returning. The reversing of the motor is automatically accomplished by the multiple switch controlling machine previously described and means have also been provided for automatically opening and closing the circuits of the motor to produce or transmit an intermittent drive through the belt 53

whether this be travelling in one direction or another. This is accomplished in the following manner:

By referring to Figs. 3 and 4, it can be seen that the names of the streets are printed or otherwise applied to the surface of the belt. Each street name is brought into register with the display opening or window 54, formed in the front of the casing 55, and means have been provided for automatically stopping the belt and motor the moment a street name is brought into register with said window. 80 and 81 indicate in general a pair of switches. They are operated by the belt 53 through the following means: Each switch consists of a pair of spring contact members 82 and 83, and pivotally mounted on the main frame as at 84 and 85 is a pair of rocker arms 86 and 87, one for each switch. Suitably secured to the outer end of each lever arm is a roller 88, and secured on the opposite edges of the belt are a plurality of raised buttons or projections 89 and 90, the projections 89 being so positioned as to engage with the roller 88 on arm 86, while the projections 90 will engage with the roller on the arm 87. There is one projection for each street and name, and these are staggered with relation to each other, that is projection 89 which registers with M Street (see Fig. 3) is offset with relation to projection 90 on the opposite side of the belt, which registers with N Street, similarly projections 89 which registers with I Street is offset with relation to projection 90 which registers with J Street, etc.

The inner end of each rocker arm is turned outwardly as indicated at 91 to bring the end of the rocker arm directly above the flexible spring contact members of the respective switches 80 and 81, with which they are connected. The operation of this part of the mechanism will be as follows:

Motor 56 having been started will transmit movement to drive the belt 53. The belt moving in a certain direction will consequently bring one of the buttons or projections into engagement with roller 88 on arm 86, and will rock this on the pivot 84, causing the outer end to move downward in the direction of arrow b, and force the flexible contacts 82 and 83 of switch 80 into engagement with each other, the buttons 90 on the opposite side of the belt being offset with relation to buttons 89, which are now in register with roller 88, will consequently permit arm 87 to remain in raised position and the contacts 82 and 83 or switch 81 will thus remain in normal or open position.

The switches 80 and 81 are automatically opened or closed through means of the buttons or projections 89 and 90 and the arms 86 and 87. These switches are connected

in such a manner that they will alternately close a by-pass or shunting circuit around the armature which is automatically opened by the multiple switch controlling machine 5 as will hereinafter be described, having reference to the wiring diagram shown in Fig. 7. This diagram illustrates the connections formed between the indicating machine and the multiple switch controlling machine and 10 in fact illustrates the wiring or connection between two indicating machines, for instance, one at each end of the street car and the multiple switch controlling machine. The circuits between the multiple switch 15 controlling machine and the driving motor of either indicating machine are identical and the description of one series of circuits is therefore thought sufficient. These circuits can be traced as follows:

20 The automatic multiple switch controlling machine controls six circuits, each of which is reversible, there being three separate circuits for each indicating machine. We will first consider a closed circuit through one 25 of the indicating machine driving motors. The motors employed, as previously described, are series wound. Current coming from the trolley line passes through a resistance 92, next through the field of the 30 motor 56 and then passes through a wire which is connected with a contact F³. The current then passes through a segment 93 on the reversing drum, a bridge wire 94, a segment 95, contact A², and then reaches 35 one terminal of the armature as at A⁴. The current then passes upwardly through the terminal A⁵ and wire A⁶ which is attached to a contact A³. The current then passes through segment 93', bridge wire 94', segment 95', and finally enters the rail or 40 ground circuit through contact G. This indicates the closed or operating circuit formed through the motor. This circuit of course causes rotation of the armature 45 and power is thereby transmitted to move the street displaying belt. This movement of the belt is however limited as the projections 89 or 90 on the belt are provided for by-passing or shunting the circuit 50 around the armature. This circuit can be treated as follows:

Current from the trolley passes through the resistance 92, the armature field 56, and then passes through a wire which is connected with contact F³, segments 93 and 95, bridge wire 94, and contact A². Current then is shunted through a wire 97 and the switch 80 of one of the indicating machines. The contacting points of said switch are 60 connected by a wire 98 with a contact J², which engages segment 99. The current passes through the segment and contact K¹, which is connected with one of the terminals of the master switch 33, by means of a wire 65 100. Current then passes through the ter-

minals of the master switch and wire 101, which is connected with the contact A³. The current then passes through the segments 93', 95', bridge wire 94', and contact G which is connected with the rail or the ground. 70 From this it can be seen that the current is grounded without passing through the armature.

It is well known that shunting or short circuiting of the armature of a motor, the field circuit remaining excited, provides an instantaneous brake for said rotating armature. This is due to the fact that the rotating armature of any direct current motor generates a powerful counter electro-motive 80 force. Shorting the armature sets up a powerful momentary field about the armature which acts as a brake. This condition takes place in the present instance the moment the contacts of the switch are closed as 85 a by-pass or shunting circuit is formed for the current. In other words the current flow through the field still continues but all flow through the armature is interrupted due to the circuit of less resistance established by 90 the switch 80. Instantaneous stoppage of the armature is therefore produced and similarly the movement of the display belt. While the current is shunted around the armature which remains stationary, it must be 95 remembered that the drum in the multiple switch controlling machine which carries the helix is rotating and that it will throw the master switch when the next street is to be displayed. Operation of the master switch 100 therefore opens the shorting circuit just described, and it also accomplishes one other function, to-wit: that of preparing a second shorting circuit through the contacts 37 on the master switch 33, adapted to be closed 105 by switch 81. The moment the master switch is thrown the current flow through the armature is again established and it is therefore obvious that movement will again be transmitted to the belt by which the street 110 names are successively displayed. Further that the belt will continue moving until the projections thereon actuated switch 81, and thereby completes the shunting circuit prepared by the master switch 33 when it engaged the contacts 37. Movement of the displaying belt will bring projections 90, formed thereon, into position where one or another of the same will actuate the contacts of the switch 81 and close the circuit 115 through the same. This second shunting being completed, instantaneous stoppage and further revolution of the motor is caused. The second shunting circuit can be traced as follows:

Commencing with the trolley the current again passes through the resistance 92, the motor field 56 and the wire which connects the same with the contact F³. The current then passes through segment 93, bridge 94, 130

segment 95, contact A^2 , wire 97, switch 81, wire 102, contact J^1 , segment 103, bridge 104, segment 105, contact K^2 , and wire 106, which connects with the master switch terminals 37. The current then passes through the said terminals and out through wire 101, which is connected with the contact A^3 , segment 93', bridge 94', contact 95', and contact G, which is connected with the rails or the ground. These are the three main circuits and they are automatically actuated by the multiple switch controlling machine and also by the movement of the display belt in the indicating machine.

15 The function of the switches 80 and 81 carried by the indicating machine and actuated by the projections on the display belt is to close the shunting circuits established by the master switch 33, and therefore causes 20 instantaneous stoppage of the driving motor 56. The function of the multiple switch controlling machine is in reality that of actuating the master switch 33, which prepares the two shunting circuits described or opens said 25 circuits.

We have other functions to consider, that 30 is the operation of the reversing switch or drum. This drum, as previously stated is automatically turned approximately one-fourth of a revolution when the car reverses at one end of a predetermined course or run. The functions of the reversing switch or drum is that of automatically reversing the circuits through the motors whereby the 35 indicating machines are driven, that is the street displaying belt travels in one direction when the car is travelling in one direction and it is therefore necessary to reverse its direction of travel when the car returns or reverses its direction of travel. The function 40 of the reversing switch or drum is therefore, first that of automatically reversing the circuits through the motors, and secondly that of reversing the shunting circuits which circuits in turn are controlled by the belt actuated switches 80 and 81, and the double master switches 33. It also serves another function hereinafter to be described. When the 45 drum assumes a position opposite to that shown in Fig. 7, it will be seen that when the motor again continues its rotation, the flow through the armature will be in the opposite direction and that the direction of rotation will therefore be reversed. This circuit can be traced as follows:

50 Current entering from the trolley passes through the resistance 92, the field coil on the motor 56, and the wire which connects the same with the contact F^3 . The current then passes through a segment 110 and out through contact A^3 , and it then passes through wire A^6 and enters the terminal A^5 on the armature, passing out through the opposite terminal A^4 it enters contact A^2 , which 55 engages a segment 111. It then passes

through this segment and out through contact G which is connected with the ground as shown. By tracing the shunting circuits through wire 97, it will be seen that the current flowing through these is also reversed. The cycle of operation in each instance will therefore be similar to those previously described, the only difference being that the current flow is reversed.

70 The main actuating drum carrying the helix is not provided with pins at terminal nor at intermediate return points and means must therefore necessarily be provided for imparting movement to the street displaying belts so that the proper street named may be displayed. The reversing switch is employed for this purpose and in such instances only serves one of the functions of the master switch, to-wit, that of opening the shunting circuits.

75 By referring to Fig. 7 it will be seen that the contacts K^1 and J^2 engage the contact 99 when the reversing switch assumes one position, and that they will engage the contacts 130 and 131 when the position of the switch 80 has been changed. By referring to the same figure it will be seen that there is a gap or break formed between the contact 99 and the contacts 130 and 131, and that the current flow through the contacts K^1 and J^2 will 90 therefore be momentarily interrupted while the switch is changing position. The contacts K^1 and J^2 control the shunting circuit around the armature and as this circuit is momentarily broken during the movement 95 of the switch, it is obvious that the current is temporarily permitted to flow through the armature of the motor. This is therefore started and movement is simultaneously 100 transmitted to the display belt in the indicating machine, the movement imparted being sufficient to move the projections formed thereon out of engagement with the switch 105 80. The shunting circuit which was first momentarily opened is thereby permanently 110 opened and it will remain open until the belt has travelled to display the proper street, and it will here be stopped due to the fact that the opposite projection 89 on the belt 115 will now engage the contacts on the switch 81 and thereby close the shunting circuit in a normal manner. The reversing switch will in this manner perform one of the functions 120 of the master switch or perform the same function as that of the pins on the helix and as no pins are provided at terminal or intermediate points, it is obvious that this special function is necessary.

125 From the foregoing description it can be seen that the automatic multiple switch controlling machine controls six circuits, three for each indicating machine and that the current flow through these circuits is reversed when the position of the reversing switch drum is changed; further the switches 130

carried by the respective indicating machines and actuated by the projections on the respective belts serve the function of completing the shunting circuits established by 5 the master switches 32 and 33, and that the function of the automatic multiple switch controlling machine is in reality that of positioning said master switches so that they either prepare the shunting circuits or open 10 the same, said multiple switch controlling machine having still another function, to-wit, that of automatically reversing all circuits when the end of a run is reached, and that of functioning as a master switch at 15 terminal or intermediate return points.

The multiple switch controlling machine really covers the subject matter of the present invention, but as its operation to a certain extent is dependent upon the switches 20 80 and 81, carried by the respective indicating machines, it is thought that their construction and operation should be described.

Having thus described our invention, what we claim and desire to secure by Letters Patent is—

1. In a device of the character described a multiple switch controlling machine, an indicating machine, an electric motor for driving the same, means actuated by the 30 multiple switch controlling machine for preparing a shunt circuit around the armature of the motor, and other means for opening the shunt circuit.

2. In a device of the character described 35 a multiple switch controlling machine, an indicating machine, an electric motor for driving the same, means actuated by the multiple switch controlling machine for preparing a shunt circuit around the armature 40 of the motor and for opening said circuit.

3. In a device of the character described a multiple switch controlling machine, an indicating machine, an electric motor for driving the same, means actuated by the 45 multiple switch controlling machine for preparing a shunt circuit around the armature of the motor, and means on the indicating machine for closing said shunt circuit.

4. In a device of the character described 50 a multiple switch controlling machine, an indicating machine, an electric motor for driving the same, means actuated by the multiple switch controlling machine for preparing a shunt circuit around the armature 55 of the motor, means on the indicating machine for closing said shunt circuit, and means actuated by the multiple switch controlling machine for opening said circuit.

5. In a device of the character described 60 a multiple switch controlling machine, an indicating machine, an electric motor for driving the same, means actuated by the multiple switch controlling machine for preparing a shunt circuit around the armature 65 of the motor, means on the indicating ma-

chine for closing said shunt circuit, means actuated by the multiple switch controlling machine for opening said circuit, and other means actuated by the multiple switch controlling machine for reversing said circuit. 70

6. In a device of the character described a multiple switch controlling machine, an indicating machine, an electric motor for driving the same, means actuated by the multiple switch controlling machine for preparing a shunt circuit around the armature of the motor, means on the indicating machine for closing said shunt circuit, means actuated by the multiple switch controlling machine for opening said circuit, a 75 reversing switch automatically operated by the multiple switch controlling machine, and means on said switch for opening the shunt circuit.

7. In a device of the character described 80 a multiple switch controlling machine, an indicating machine, an electric motor for driving the same, a master switch in the controlling machine, an automatically actuated switch in the indicating machine adapted to close a shunt circuit around the armature of the motor, and means actuated by the multiple switch controlling machine for automatically changing the position of the master switch to open said shunting circuit. 85

8. In a device of the character described a multiple switch controlling machine, an indicating machine, an electric motor for driving the same, a master switch in the controlling machine, an automatically actuated switch in the indicating machine adapted to close a shunt circuit around the armature of the motor, and means actuated by the multiple switch controlling machine for automatically changing the position of the master switch to open said shunting circuit and simultaneously prepare a second shunting circuit. 100

9. In a device of the character described a multiple switch controlling machine, an indicating machine, an electric motor for driving the same, a double throw switch in the controlling machine adapted to open and also adapted to prepare a shunting circuit around the armature of the motor, 110 and an automatically actuated switch on the indicating machine adapted to close the shunting circuit prepared by the double throw switch. 115

10. In a device of the character described 120 a multiple switch controlling machine, an indicating machine, an electric motor for driving the same, a double throw switch in the controlling machine adapted to open and also adapted to prepare a shunting circuit 125 around the armature of the motor, an automatically actuated switch on the indicating machine adapted to close the shunting circuit prepared by the double throw switch, and a reversing switch in the controlling 130

- machine adapted to reverse the current flow through the motor and also through the shunting circuit.
11. In a device of the character described 5 a multiple switch controlling machine, an indicating machine, an electric motor for driving the same, a double throw switch in the controlling machine adapted to open and also adapted to prepare a shunting circuit around the armature of the motor, an 10 automatically actuated switch on the indicating machine adapted to close the shunting circuit prepared by the double throw switch, and a reversing switch in the controlling machine adapted to reverse the current flow 15 through the motor and also through the shunting circuit, said reversing switch, when changing position, also adapted to open the shunting circuit.
12. In a device of the character described 20 a multiple switch controlling machine, an indicating machine, an electric motor for driving the same, a shunt circuit formed around the armature of the motor, a double throw master switch in the controlling machine adapted to open the shunting circuit and also adapted to prepare the shunting circuit around the armature, power driven means adapted to intermittently 25 change the position of the master switch, an automatically actuated switch in the indicating machine adapted to close the shunting circuit prepared by the master switch, a reversing switch in the controlling machine adapted to reverse the current flow 30 through the motor and also through the shunting circuit.
13. In a device of the character described 35 a multiple switch controlling machine, an indicating machine, an electric motor for driving the same, a shunt circuit formed around the armature of the motor, a double throw master switch in the controlling machine adapted to open the shunting circuit and also adapted to prepare the shunting circuit around the armature, power driven means adapted to intermittently change the 40 position of the master switch, an automatically actuated switch in the indicating machine adapted to close the shunting circuit prepared by the master switch, and a second automatically actuated switch in the indicating machine adapted to close the next 45 shunting circuit prepared by the master switch and said master switch automatically opening the shunting circuits closed by the indicating machine switches.
- In testimony whereof we have hereunto set 50 our hands in the presence of two subscribing witnesses.
